UNITED STATES PATENT OFFICE.

EGBERT W. GILLETT, OF CHICAGO, ILLINOIS.

BLUING-PACKAGE.

SPECIFICATION forming part of Letters Patent No. 256,995, dated April 25, 1882.

Application filed February 13, 1882. (No model.)

To all whom it may concern:

Be it known that I, EGBERT W. GILLETT, of Chicago, in the county of Cook and State of Illinois, have invented certain new and useful 5 Improvements in Bluing Packages or Holders, of which the following is a specification.

The object of my invention is to provide a package or holder for the lump or powdered bluing used for laundry purposes of such a character as will serve not only as a receptacle for the bluing in shipment and when sold in small quantities, but will further serve, while still retaining the same, as an effective means for thoroughly and uniformly imparting to the 15 water the coloring-matter in any desired tint. This object of my invention I best accomplish by first inclosing the bluing within a small bag of suitable fabric, which is then inserted within a hollow reticulated or open-work receptacle 20 provided with an extension, by which such receptacle may be readily manipulated while submerged in the water to be colored. In practice, also, I find it desirable to provide the receptacle with what I designate a "drip-cup," 25 the construction and function of which will be hereinafter more fully described.

It is customary to form the handles of a great variety of implements—such, for example, as ice-picks, stove-lid lifters, tack-hammers, pokers, and many small tools—with hollow reticulated or open-work handles, usually made of cast metal. It is to this class of implements 30 that my present invention has especial adaptation, since the handles serve as the holder for the bluing inclosed within a bag, while the body of the implement answers readily for manipulating the same in the water.

In the accompanying drawings I have shown a stove-lid lifter modified, as will be described, 35 that it may better attain the purposes of my invention.

Figure 1 shows a front view of such lifter embodying my improvement, and Fig. 2 shows a longitudinal section of the same.

45 A represents the body of the implement, and B designates the elongated hollow reticulated or open-work handle of the same, into which is placed the small bag C, containing the bluing. The end portion of this hollow reticulated handle, as will be seen, is made with an imperforate or solid surface to form a drip-cup,

D, of considerable depth, into which for a short distance is inserted the flat cork or stopple E, serving to retain the bluing-bag in the handle and constituting the bottom of such cup. In the opposite end of the implement an aperture, a, is made, by which it may be suspended from a suitable support. In implements of this class as heretofore made, so far as I am aware, the imperforate portion D has been 55 very shallow and has not been provided with a stopple nor with an aperture in the end, since these features become of use only when carrying out my present improvement.

The manner of applying my invention is as 60 follows: The lump or powdered bluing, inclosed within a bag of suitable fabric, is placed within the hollow reticulated handle, into the end of which the cork or stopple is tightly fitted. In this condition the package is ready for the 65 market, and when water is to be colored for laundry purposes the receptacle D is immersed therein and a stirring action given thereto. By reason of the reticulated or open-work form 70 of this receptacle the water comes freely into contact with all parts of the inclosed bag, and is rapidly and uniformly colored. When the desired tint has been obtained the implement is withdrawn and suspended from a suitable support, passing through the aperture of the 75 end, the drip-cup serving to catch and retain any bluing which would otherwise be wasted and would discolor the floor.

Heretofore it has been customary to inclose 80 lump or powdered bluing within bags, which were dipped in the water to be colored; but these bags were liable to burst in transportation and handling, afforded no means for agitating and equally coloring the water, and when withdrawn therefrom were liable to discolor surrounding objects with which they 85 came in contact.

I am aware that it has been proposed to construct a bluing implement consisting of a handle provided upon its end with a cup, into which 90 the powdered bluing is packed, and in which it is retained by a piece of muslin tied over the top of the cup. It is obvious that in such construction so great a surface of bluing is not exposed to the water as in my improvement, and, 95 moreover, by repeated use the exposed muslin cover is liable to wear and fall off, and so dis-

charge at once the entire contents of the cup. Furthermore, no provision is there made for catching the drippings after use.

Another mode of packing bluing of which I am aware is to inclose the same in a suitable bag, which is placed within a glass bottle provided with perforations at its bottom. This last form of package is somewhat expensive, requiring, as it does, a special construction of bottle suited to this single purpose, which is liable to be broken, affords no such ready means as does my improvement for manipulating the package in the water, has no provision for catching the drippings when taken therefrom, and the small perforations at the bottom do not expose so large a surface of the bluing-bag to the action of the water and are liable to become stopped up.

I am also aware that a bluing-package has heretofore been made consisting of a reservoir formed of two hemispheres of sheet metal, the upper one being perforated around its center, and both being connected together by a rod which passes through them and is lengthened upon one side to form a handle. This construction of package, consisting, as it does, of several separate parts, I have found much more expensive and complicated than that of my present invention; and, furthermore, it was not adapted to receive bluing inclosed within a bag, nor did the small perforations permit the water to be so speedily colored.

It is obvious that the construction of my holder, as above described, may be somewhat modified without departing from the spirit of my invention. Thus, for example, when a drip-cup is not used the stopple in the end of the

bluing-receptacle need not be solid, but may be of any suitable form which will serve to retain the bulk of bluing in place.

By my present invention I am enabled to furnish to consumers a package or holder for laundry-bluing which is safe, effective, and cleanly, and which without material increase of cost, when no longer required for such purpose, is equally adapted for other uses.

Having thus described my invention, what I claim as new, and desire to secure by Letters Patent, is—

1. A holder for laundry-bluing, consisting of a hollow reticulated and open-ended receptacle provided with a removable stopple and with an extension, substantially as described, whereby the receptacle may be manipulated as set forth.

2. A holder for laundry-bluing, consisting of a hollow reticulated and open-ended receptacle having a removable stopple, which forms therewith a drip-cup, said receptacle being provided with an extension, substantially as described, to manipulate the same, as set forth.

3. As an article of manufacture, a hollow reticulated open-ended receptacle in which a mass of laundry-bluing is sustained, substantially as described, said receptacle being provided with an extension or handle to manipulate the same, and adapted as well for use as a tool, substantially as set forth.

EGBERT W. GILLETT.
